United States Patent Office.

JOSEPH K. ANDREWS, OF ANTRIM, OHIO, ASSIGNOR TO HIMSELF AND
J. C. TILTON, OF PITTSBURG, PENNSYLVANIA.

Letters Patent No. 66,278, dated July 2, 1867.

IMPROVEMENT IN LAMPS.

The Schedule referred to in these Letters Patent and making part of the same.

TO ALL WHOM IT MAY CONCERN:

Be it known that I, JOSEPH K. ANDREWS, of Antrim, in the county of Guernsey, and State of Ohio, have invented a new and improved Lamp-Burner; and I do hereby declare that the following is a full, clear, and exact description thereof, which will enable one skilled in the art to make and use the same, reference being had to the accompanying drawings, making part of this specification, in which—

Figure 1 is a vertical central section through the section line C D of fig. 2

Figure 2 is a vertical central section through the section line A B of fig. 1.

Similar letters of reference indicate like parts.

My invention consists of a gauze or perforated metal cylinder with a metal cap, a gas-generating tube protruding through the cap, and an inside cone, all attached by a hinge to an elevated kerosene lamp-burner, together with a small tube or tubes burning the oil direct and in connection with the gas, making a strong, steady, and inodorous flame, readily consuming the smoke, dispensing with the glass cylinder, and which can be carried in the wind without being extinguished.

E represents my lamp-burner, which is elevated some distance above the screw-cap F of the lamp by the wick-tubes G and O, and supported by the same. The cylinder H is of gauze or perforated metal hinged to the perforated metal chamber I, giving a free circulation of air to all the parts. K is a metal cone with vents L L on each side of the gas-tube M, which is perforated, slotted, cut into teeth or points at the lower end, as is clearly shown in the drawing, for the purpose of smothering the wick. It is semicircular at the top, protruding above the solid cap N, and closely fitted to the same. O is an independent wick-tube burning the oil direct. The semicircular slot P is for the purpose of collecting the surplus gas which escapes from the gas-tube M, by which arrangement the gas and smoke are thoroughly consumed.

I disclaim everything claimed in a patent granted me July 11, 1865. I also disclaim everything claimed in a patent granted me November 18, 1866.

What I claim as new, and desire to secure by Letters Patent, is—

1. The gas-tube M, perforated, slotted, projecting above the cap N, cut at the lower end, and constructed as shown in fig. 2 of the accompanying drawing.

2. The adoption of the tube or tubes O burning the oil direct in combination with the gas, constructed and operating substantially as and for the purpose set forth

J. K. ANDREWS.
